(57) CLAIM

The ornamental design for a double herb mailing container with root pockets, as shown.

DESCRIPTION

FIG. 1 is a front top perspective view of a double herb mailing container with root pockets showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom view thereof.
